UNITED STATES PATENT OFFICE

THOMAS W. FLESHNER, OF LOS ANGELES, CALIFORNIA.

MEANS FOR DATING AND IDENTIFYING TICKETS.

1,247,807.

Specification of Letters Patent. Patented Nov. 27, 1917.

Application filed December 18, 1916. Serial No. 137,484.

To all whom it may concern:

Be it known that I, THOMAS W. FLESHNER, a citizen of the United States, residing at Los Angeles, in the county of Los Angeles and State of California, have invented a new and useful Means for Dating and Identifying Tickets, of which the following is a specification.

This invention relates to a means and method for dating and identifying tickets such as railway and other transportation tickets. The primary object of the invention is to provide for the identifying of each ticket sold with the salesman authorized to sell tickets on the date stamped thereon, so that the unauthorized sale of tickets may be determined.

Another object of the invention is to provide an identification die or stamp which is adapted to coöperate with the dating die and the company and location stamp of the ordinary type of ticket dating machine so that the identification marks by which the salesmen are known will appear upon the tickets, the die or stamp being constructed so that it may be readily removed from the ordinary dating machine and carried by the salesman identified thereby in order that a salesman on going off duty may remove his identification die from the machine and the salesman taking his place may place in the machine his identification die.

The accompanying drawings illustrate the invention.

35 Figure 1 is a side elevation of the dating machine of well-known construction equipped with my improved die;

Fig. 2 is a top plan view of the die assembled;

40 Fig. 3 is a top plan view of the identification element forming a part of the die;

Fig. 4 is a bottom view of the main portion of the die;

45 Fig. 5 is a bottom view of the identification element; and

Fig. 6 is a cross sectional view taken on line 6—6 of Fig. 2;

Fig. 7 is a detail view of the bed;

50 Fig. 8 is a view of the imprint made by the complete die as it appears on a ticket.

Referring to the drawings, 1 designates as an entirety a dating machine of well-known construction which includes a body portion 2, stamping member 3 pivoted there-to at 4, and a die receiving recess 5 which receives my improved die 6.

The die 6 comprises in this instance a rec-

tangular metal plate 7 which constitutes the main or body portion of the die, and a rectangular die member 8 interfitting with the plate 7 and carrying the identification characters. The plate 7 is for the most part formed as a majority of the dies for dating machines, there being provided a central opening 9 into which extends the dating members 10 of the machine 1. Adjacent to the opening are suitable letters or characters 11 which identify the particular railroad or company issuing the ticket. Preferably at diametrically opposite points there are provided identification die-receiving openings 12.

The die member 8 has upstanding projections or lugs 13 formed on the upper face thereof and the identification characters 14 are formed in the upper faces of these lugs or projections. Thus the die plate 7 is thinner than some portions of the die member 8 so that, though it would be possible to place the die member 8 in the die-receiving recess without the die plate 7, it is not possible to use the die plate 7 alone for validating tickets in the machine. Upon its under face the plate 7 is provided with flat faced projections 15 near the corners thereof, the projections being joined in pairs by ribs 16 whose outer faces are flush with the flat outer faces of the projections. The projections 13 are carried upon lateral extensions 17 that are formed integral with the frame 8 and extend inwardly toward one another from certain opposed inner edges of said frame, the inner edges of said extensions 17 engaging the ribs 16. The under faces of the extensions 17 are provided with recesses 18 adapted to receive lugs 19 carried on the body portion 2 of the machine 1 and located within the recess 5.

In assembling the die, the plate 7 is placed upon the member 8, the member and plate being of the same dimensions so that their edges come flush with one another. The projections 13 engage in the die-receiving openings 12 and the upper faces thereof lie flush with the upper face of the body plate 7. When the die is thus assembled it may be placed in the recess 5 and will be held against slipping by the lugs 19 on the body of the machine which engages within the openings 19 in the member 8 of the die.

The die plate 7 is the same as the ordinary die plates generally used in dating machines with the exception of the under face construction and the die-receiving openings.

12, this latter change in construction making the plate adaptable for use in connection with the identification element of the die. It is to be understood that while 5 I have shown the dies as substantially square in outline, that they may be of other shapes.

In using my invention for dating railway tickets, each ticket salesman is provided with an identification die member 8, any of these members 8 being adapted to fit into the plate 7, as shown in Figs. 1, 2 and 6 of the drawings. When the salesman assumes his duties he fits his particular 15 identification die member into the plate 7 which carries the characters identifying the particular road or company and places the die when thus assembled into the recess 5. The dating machine is operated in the 20 ordinary manner and each ticket sold by the particular salesman bears his identification mark which will make it possible to trace the sale of each ticket.

It will be seen that an effective method 25 of dating and identifying tickets may be carried out with my invention, such method consisting of the marking or stamping the time of sale of tickets together with the identification marks by which the sales of 30 tickets are identified, at the time of sale of the tickets and upon the date of sale. Therefore it will be seen that mechanically my invention comprises the provision of an 35 identification die or stamp which will coöperate with the main die or stamp of a dating machine so that the foregoing method may be carried out and a compact and simply constructed die as a whole may be provided.

40 I claim:

1. A dating machine die for railway tickets comprising a main die plate having a central opening therein to receive the 45 dating die of a dating machine and an opening to one side of the main opening, a second die plate of the same dimensions as the first named die plate and interfitting with said first named die plate beneath the latter, and an identification die on said last 50 named plate extending through the last named opening of the first named plate to cause a mark to appear on the ticket which will identify the seller of the ticket so that the unauthorized sale of tickets may be determined.

55 2. The combination with a dating machine die for railway tickets including a dating machine body having a main die plate receiving recess therein, a stamping 60 member above the recess, a dating die and a main die plate in the recess, of an identification die plate mounted within the recess and extending beneath the main die, co-

operating with the main die plate and having certain opposed edges thereof engaged 65 with certain opposed walls of the recess.

3. The combination with a dating machine having a body portion formed with a die plate receiving recess and having a die plate therein, a stamping member above 70 the recess and a dating die, said die plate having an opening therein, of an identification die plate mounted within the recess and extending beneath the first named die plate and having a die thereon extending 75 into the opening in the first named die plate.

4. The combination with a dating machine having a body portion formed with a die plate receiving recess and having a 80 die plate therein, a stamping member above the recess and a dating die, said die plate having an opening therein, of an identification die plate mounted within the recess and extending beneath the first named 85 die plate and having a die thereon extending into the opening in the first named die plate, and certain edges of the identification die plate engaging certain opposed walls 90 of the recess.

5. The combination with a dating machine having a body portion provided with a main die plate receiving recess therein and a main die plate mounted within the recess, of an identification die 95 plate mounted within the recess and extending beneath the main die plate and having certain edges thereof engaging certain opposed walls in the recess, said main die plate having openings therein, and identification dies on the identification die plate extending through the openings in the 100 main die plate.

6. The combination with a dating machine body having a die-receiving recess 105 therein, of a stamping member above the recess, a main die plate in the recess of less thickness than the depth of the recess, and an identification die plate mounted in the recess and having a portion of greater 110 thickness than the main die plate.

7. A ticket validating system comprising a main die plate, and interchangeable identification die plates, each identification die plate having thereon an identification character differing from the identification characters on the other die plates and any one of said identification die plates being adapted to support and coöperate with the main die plate for stamping a ticket.

Signed at Los Angeles, California, this 9th day of December, 1916.

THOMAS W. FLESHNER.
